GLIDER HOOK FOR SASH BALANCES

James B. Jessup, Burbank, Calif., assignor to
Duplex, Inc., West Hollywood, Calif., a corpora-
tion of California

Application April 1, 1940, Serial No. 327,155

8 Claims. (Cl. 16—205)

This invention relates to glider hooks for use in connection with sash balances and has a particular application in connection with a spring sash balance such as illustrated in my copending application, Serial No. 327,156 filed April 1, 1940, and with other forms of sash balances.

In the type of spring sash balance mentioned a spiral coil spring mounted on an axle within a housing is installed in the pulley stile or jamb, and the action of the spring is opposed to the weight of the sash, a cable carrying drum associated with the spring being operatively connected with the sash by flexible wire, tape or cable, the latter of which rolls up on the drum in the housing as the sash is raised, and unwinds from the drum as the sash is lowered.

It is necessary in that connection to have a satisfactory connecting device between the end of the cable or other connecting element and the sash which will adequately secure the cable end to the sash at the proper position. It is also desirable that this connecting device be formed with a friction spring which will perform two primary functions: first, that of governing movement of the sash against the stile, and second, to properly position the sash with respect to the stile and to prevent sagging or creeping of the sash.

My present invention is an improvement over glider hooks of that general type.

It is an object of my invention to provide an improved form of glider hook of the type mentioned which is more sturdy and durable than those known to the prior art.

It is a further object of my invention to provide in a glider hook of the character described a simplified and improved assembly of the parts and attachment of the wire cable or other connecting element to the hook.

It is a further object of my invention to provide a device of the character described which has no rough edges on the stile engaging face thereof which might tend to mar the stile or improperly drag thereon, but which on the contrary is quite smooth on the outside and eliminates all possibility of undesirable scratching or dragging on the stile.

My glider hook is described particularly in connection with an installation in a window frame assembly. It, of course, has other applications in cabinet construction and the like which will be obvious to anyone skilled in the art.

Additional objects and advantages of my invention will become apparent upon a reading of

the following description and reference to the drawing.

In the drawing:

Figure 1 is a front elevation of a part of a window frame assembly illustrating my glider hook in use.

Figure 2 is an enlarged fragmentary view taken at the lower left hand corner of Figure 1 and showing the glider hook in vertical section.

Figure 3 is a front elevation of the glider hook itself taken in the direction of the arrow 3 of Figure 2.

Figure 4 is a view of the same device as Figure 3 looking at it from the opposite side.

In the drawing, 10 represents a conventional window stile, 11 is one sash, and 12 is a spring sash balance of the general character described from which extends a wire cable 13 to the lower end of which is attached my improved glider hook 14. It is obvious that in place of the spring sash balance 12 any other type of spring sash balance equipment may be substituted, but I prefer to illustrate my invention in connection with the preferred type of flat sash balance equipment. It will be understood that in the spring sash balance 12 there is a spring tensioning element which tends to draw the cable 13 upwardly and thus counteract the weight of the sash. The same device is applicable either to the upper or lower sash of a window and the spring sash balance may contain twin units, one for each sash. I may also, if desired, use a balance at each side of the pulley stile, one being a duplicate of the other.

My preferred form of glider hook comprises an L shaped bracket member 15, having inturned flanges 16 on its vertical edges as illustrated, and a horizontal part 23 formed with a rib to increase rigidity if desired. The upper edge of the vertical portion is preferably turned inwardly and downwardly to form a horizontal flange 17 with a central recess 18 for the entrance of the wire cable or element 13. A hollow boss 19 is struck inwardly from the upper portion of the vertical part of the bracket to form a seat for the cable 13 and an anchor for a spring member hereinafter described. Of course, a common rivet could be welded or otherwise secured to the inner face of the vertical extension in lieu of the hollow boss which is struck inwardly, or some other arrangement for attaching the cable and spring may be employed, but the simplest and most effective way of fabricating this piece is as first described. Moreover, the hollow boss provides a hole by which the hook may be mounted on an

intermediate point on the side of the sash, also to facilitate installation. For this purpose the hook may be temporarily lodged on a nail driven part way into the stile, while the sash is being placed into the frame.

The lower end of the cable 13 is wrapped around the boss 19 and the free end of the cable may be twisted around itself, but this is not necessary, as it is ordinarily sufficient to bring the free end of the cable up through the slot 18 as illustrated in Figures 3 and 4. Other means of attachment may be employed, as for instance, running the cable through the hole in the boss, and securing the end of the cable.

A horizontal slot 20 is formed in the vertical part of the bracket 15 extending the major portion of the width of the bracket.

A leaf spring 21 is inserted through this slot 20. The spring has a wide curve as illustrated, with a rounded and inwardly turned lower end. That part of the spring which extends outwardly from the slot 20 is preferably approximately the same width as the bracket member 15. I also prefer to offset the spring inwardly as at 22 to accommodate the slightly narrower dimensions of the slot 20 as well as to comfortably seat on the inside of the flanged portion at the upper part of the bracket. In my preferred form as described the spring is provided with a hole to accommodate the annular boss 19.

In assembling the preferred form of my device, the cable is first positioned on the boss, the spring is next placed in the bracket, and the inner ends of the boss are spread with any suitable tool as illustrated in Figure 2 to rivet the parts together. The clamping flanges 17 on the upper end of the vertical member, which up to this point in manufacture, extended at right angles thereto, are now clamped down over the upper end of the spring.

The assembly steps described to this point are preferably made at the factory in conjunction with the spring sash balance. The horizontal lower part 23 of the bracket 15 is formed with holes to accommodate screws or nails, or it may be equipped with a prong or some other form of means to attach it to a sash.

The glider hook is installed by placing it flush with the lower corner of the sash and attaching it by means of screws or nails as illustrated. It is desirable to let it into the bottom of the lower sash, and possibly to gain it in the side of both upper and lower sash, depending upon the clearance allowed by the installer.

In use, my improved glider hook performs several functions: First, it provides for the attachment of the tensioned cable 13 to the proper point on the sash; second, it provides a frictional engagement, in effect between the sash and the stile, to govern relative movement of those two parts and consequently to assist in maintaining the sash at the position where manual movement thereof has stopped; third, the spring action of my glider hook prevents the sash from sagging or creeping, that is to say it maintains the window vertically and urges the opposite side into flush engagement with the corresponding stile, thus maintaining the sash in proper perpendicular position and eliminating the necessity of any roller or friction device on the opposite side of sash. The combination of forces offered by the tensioned cable and the spring action of my glider hook assure that the sash will remain in a true perpendicular position. The same effect is obtained if a duplicate of the sash balance and

glider is used on the opposite side of the sash. In other words, it will work on either side or will work in pairs, one opposing the other. In case 5 a device is used on each side of the sash the latter will be truly centered between the stiles and there will be the equivalent clearance between sash and stile on each side.

In previous types of glider hook it has sometimes occurred when the wooden parts swelled or when the installation or workmanship was poor and the clearance between sash and stile was thus diminished that parts of the glider hook improperly engaged the stile and marred it as well as preventing correct operation of the sash.

In my present device this is impossible for the reason that there are no rough or irregular edges or projections which can come in contact with the stile. The outside of my glider hook is perfectly smooth at every point. Even if the clearance between sash and stile is diminished so that the spring is entirely compressed it will still operate smoothly and the spring will function with the proper frictional resistance against the stile. Another special advantage of the present construction of glider hook is in the arrangement of the spring fulcrum at the point where the spring passes through the slot 20. There is a double fulcrum action there on the opposite faces of the spring.

Consequently the turned over edge of the annular boss 19, and the clamping flanges 17 are not subject to any severe strain (which has been present in previous types of glider hooks with which I am familiar and which under severe pressure or abuse may pull apart). The riveting action of the annular boss 19 and the flanges 17 in my present device is required only to retain the cable and the upper end of the spring in position. Once the spring is installed in this manner there is but a very slight spring pressure exerted against the turned over edges of the retaining boss 19, or the clamping flanges 17.

Various modifications constituting equivalents may be made in the details of the device within the scope of my invention. The spring, illustrated as a leaf spring, may be any formed spring having a similar longitudinal contour in cross section, and my reference in the claims to a leaf spring is intended to be so construed.

What I claim as my invention is:

1. A glider hook of the character described comprising a bracket member for attachment to a sash, said member being formed with a slot for the reception of a leaf spring, a spring retaining boss extending inwardly from said bracket, and a leaf spring fulcrumed in the said slot having a portion extending outwardly from the bracket for frictional engagement with a member external thereof and a portion extending upwardly inside the bracket and mounted on the said boss.

2. The combination of: a glider hook of the character described comprising a bracket for attachment to a sash, said member being formed with a slot for the reception of a leaf spring, a cable and spring retaining boss extending inwardly from said bracket, a wire cable having its end looped around said boss, a leaf spring fulcrumed in the said slot having a portion extending outwardly from the bracket for frictional engagement with a member external thereof and a portion extending upwardly inside the bracket and mounted on the said boss against the loop of the wire cable, and means on the inner end of the boss securing the cable and upper end of the spring to the boss.

3. A glider hook of the character described comprising a bracket for attachment to a sash, said member being formed with a slot for the reception of a leaf spring, a spring retaining hollow boss struck inwardly from the face of the bracket, and a leaf spring fulcrumed in the said slot having a portion extending outwardly from the bracket for frictional engagement with a member external thereof and a portion extending inside the bracket and mounted on the said boss; and means on the inner end of the boss securing a cable and upper end of the spring in place.

4. A glider hook of the character described comprising a bracket formed with a horizontal slot for the reception of a leaf spring, and a leaf spring secured at its upper end to the bracket and fulcrumed in the said slot, having a portion extending outwardly from the bracket and having a rounded and inwardly turned lower end for frictional engagement with a member external thereof.

5. A glider hook of the character described comprising a bracket formed with a slot for the reception of a leaf spring, and a leaf spring having a portion extending upwardly inside and secured to the bracket and having a portion extending through said slot and outwardly from said bracket with a rounded and inwardly turned lower portion for frictional engagement with a member external thereof.

6. A glider hook of the character described comprising a bracket formed with a slot, a leaf

spring fulcrumed in said slot and secured at its upper end only inside the bracket and having an outwardly extending curve portion with the end free for frictional engagement with a member external thereof, and pressural means for attaching the leaf spring and a cable to the bracket.

7. A glider hook of the character described comprising a bracket member for attachment to a sash, said member being formed with inturned flanges which provide means to position a cable and a leaf spring, said bracket member having a smooth external surface, a slot formed in the said bracket member for the reception of the leaf spring, and a leaf spring fulcrumed in the said slot having a portion extending outwardly from the bracket for frictional engagement with a member external thereof.

8. A glider hook of the character described comprising a bracket member formed with a slot for the reception of a leaf spring, a leaf spring extending through the slot and fulcrumed on an edge of the slot, means retaining one end only of the spring for fixed pressural engagement against the inside of the bracket member, and the opposite end of the spring being free of the bracket member and formed with a smooth outer surface for pressural sliding engagement with an external surface, so that when the spring is compressed the only longitudinal movement thereof will be at its lower end.
